UNITED STATES PATENT OFFICE.

PATRICK W. EGAN, OF WEST CHESTER, PENNSYLVANIA.

GAS-ENGINE.

1,008,800.

Specification of Letters Patent. Patented Nov. 14, 1911.

Application filed July 11, 1910. Serial No. 571,266.

To all whom it may concern:

Be it known that I, PATRICK W. EGAN, a citizen of the United States, residing at West Chester, in the county of Chester and State of Pennsylvania, have invented certain Improvements in Gas-Engines, of which the following is a specification.

My improvements in gas engines relate to means for regulating the charge admitted to the cylinder, for the purpose of governing the speed of the engine and obtaining high efficiency.

In the preferred construction, a rotary valve, having several ports extending there-through transversely to its axis, is placed in the passage connecting the cylinder of an engine with the chamber to which the charge is admitted and in which it is compressed, and the action of the engine is regulated by regulating the position of the valve by mechanism comprising a governor acting through means for effecting a quick movement, the mechanism being operated so as to obtain the desired port area of the valve and the delivery of the desired supply of gas to the cylinder at the instant requisite for obtaining the maximum efficiency.

In the accompanying drawings, Figure 1 is a sectional side elevation of a gas engine embodying my improvements; Fig. 2 is a sectional elevation at right angles to the position shown in Fig. 1; and Fig. 3 is a transverse sectional view of the valve shown in the open position in the passage which connects the crank chamber with the cylinder.

In the construction, as shown in the drawings, the crank chamber 1 and the cylinder 2 are connected by the passage 3 having the port 4 communicating with the crank chamber and the port 5 communicating with the cylinder; the cylinder containing the piston 6 connected by the rod 7 with the crank 8 of the shaft 9 which is journaled in bearings 10.

45 A cylindrical valve 11, having ports 12 separated by the diametrical web 13, is journaled in the seat 14 and controls the passage 3. The ports are equal in cross sectional area and when fully opened have their outer faces flush with the corresponding walls of the passage, so that the port area is changed proportionately to the rotation of the valve and the total port area is variable at double the rate obtaining in the use 55 under like conditions of a single port. A

pinion 15 is fixed to the valve 11 and is revolved by a larger pinion 16 journaled on a bearing 17, the pinion 16 being revolved by an arm 18 fixed thereto and connected through a link 19 with a lever 20 fulcrumed to the bearing 21. A collar 22 is loosely mounted on the crank shaft 9 (or an extension 10' of the bearing 10) and is provided with a circular channel 23 into which extends a fork 24 connected with the lever 20; the collar being movable longitudinally to adjust the position of the lever, which acts through the link 19, arm 18, pinion 16 and pinion 15 to regulate the position of the valve.

The fly wheel 25, fixed on the shaft 9, carries bearings 26 on which are fulcrumed crank levers comprising the arms 27 pivotally connected to the collar 22 and the arms 28 provided with the weights 29. These weights are connected, suitably, by providing them respectively with laterally extending projections 30 and connecting the projections by springs 31, the tension of the springs being adjustable by screws 32. The weights are held by the springs in their inner position and the valve is normally held 70 open by the intermediate mechanism.

Initially the valve is in the fully open position. As the speed of the engine rises so 85 that the centrifugal action of the balls is sufficient to overcome the tension of the springs, the balls move outwardly, the collar is drawn toward the fly wheel and the lever is caused to act, through the link and 90 arm, upon the pinions, by which the valve is revolved and the passage closed proportionately to the rise in speed, thus regulating at the desired instant the quantity of gas delivered from the crank chamber to the 95 cylinder by the pulsatory action of the engine, it being understood that the chamber communicates with the cylinder in the rear of the piston.

Having described my invention, I claim:— 100

1. A gas engine comprising a cylinder, a piston therein, a passage leading to said cylinder, a rotary valve for controlling said passage, a pinion fixed to said valve, a larger rotary pinion engaging said pinion first 105 named, and mechanism comprising a governor whereby said piston operates said rotary pinion.

2. A gas engine comprising a cylinder, a piston therein, a rotary shaft, means where- 110

by said piston revolves said shaft, a passage leading to said cylinder, a valve for regulating said passage, a pinion fixed to said valve, a second pinion engaging said pinion first named, means comprising a lever for turning said second pinion, a collar movable longitudinally, said collar engaging and rocking said lever, a fly wheel on said shaft, and a centrifugal governor connecting said wheel

and collar whereby said valve is gradually closed as the speed of the engine rises.

In witness whereof I have hereunto set my name this 8th day of July, 1910, in the presence of the subscribing witnesses.

PATRICK W. EGAN.
